Primary Examiner—Jeffrey Asch*Attorney, Agent, or Firm*—Myers Bigel Sibley & Sajovec, P.A.**[57] CLAIM**

The ornamental design for elastomeric tactile surfaces for a radiotelephone, as shown and described.

DESCRIPTION

FIG. 1 is a perspective view of the elastomeric tactile surfaces for a radiotelephone showing my new design in the environment of a radiotelephone;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines shown herein are for illustrative purposes only and form no part of the claimed design.

The boundary of the article, not shown by means of a solid line at the top right in FIGS. 1 and 6, is defined by, but does not include, the broken line therein.
